UNITED STATES PATENT OFFICE.

SALVATORE SCOGNAMILLO, OF NEW YORK, N. Y., ASSIGNOR TO AUTOMOBILE SUPPLY MANUFACTURING COMPANY, OF BROOKLYN, NEW YORK.

FLEXIBLE TUBING.

SPECIFICATION forming part of Letters Patent No. 781,560, dated January 31, 1905.

Application filed June 22, 1904. Serial No. 213,689.

To all whom it may concern:

Be it known that I, SALVATORE SCOGNAMILLO, a citizen of the United States, residing at New York, in the county of New York and State 5 of New York, have invented new and useful Improvements in Flexible Tubing, of which the following is a specification.

This invention relates to flexible tubing or metallic spiral hose; and the primary object 10 of the same is to provide a casing composed of a spirally-wound metal strip having yielding interlocking or overlapping members of a specific contour and inclosing a packing-strip to form a reliable jointure, the casing 15 being fitted over an inner resilient sustaining-coil of wire, the convolutions of the latter forcefully intersecting the inner portions of the convolutions of the metal strip and firmly holding the joints of said metal strip intact, 20 and also operating to resist crushing strain.

A further object of the invention is to form a tube having increased longitudinal strength and freely bendable laterally to accommodate itself to any and all uses to which an article 25 of this class is applicable.

With these and other objects and advantages in view the invention consists in the construction and arrangement of parts, which will be more fully hereinafter set forth.

30 In the drawings, Figure 1 is a view in elevation of a tube embodying the features of the invention. Fig. 2 is a view of the same in longitudinal section. Fig. 3 is a detail view of a portion of the tube, particularly 35 illustrating the joint between the constituents of the tube, on an enlarged scale.

Similar numerals of reference are employed to indicate corresponding parts in the several views.

40 The numeral 1 designates a metal strip of suitable width and spirally wound to form an inclosing casing of metal. This strip is bent by suitable means to provide an outer box-like member 2, with an inwardly-curved flange 3, and a concave seat member 4, with an outwardly-bent terminal 5. The flange 3 of the box-like member is movably fitted in the concave seat member 4 of the adjacent convolu-

tion throughout the entire spiral winding of the strip, and within the inclosure thus formed 50 a packing strip or cord 6 is interposed and preferably circular in cross-section. The packing strip or cord 6 is directly embraced by the flange 3, the inner portion of the seat 4, and the outwardly-bent terminal 5 of said 55 seat, and between the several seats a space 7 is provided, which is snugly engaged by the convolutions 8 of an inner sustaining-spring 9, of wire. The convolutions of the inner sustaining coil or spring 9 regularly intersect the spaces 7 and institute an expanding pressure longitudinally, as well as radially, against the seats 4 and flanges 3, and the greater the external pressure on the tubing or hose the tighter the joints will be compressed around the packing-strip inclosed in the bent members of the metallic strip. The 60 interlocked convolutions of the metallic strip are loose enough, however, to permit the tubing to be arcuately bent in opposite directions 65 and also to allow for longitudinal expansion and contraction to accommodate various applications and conditions which will affect the 70 constituents of the tubing.

The improved tubing or hose can be readily 75 manufactured and the parts quickly assembled, owing to the disposition of the same, and the most expeditious method consists in first forming the inner sustaining-coil and applying the outer strip thereover, at the same 80 time feeding the packing-strip into the seats 6 as the latter are shaped. It will also be understood that changes in the proportions and dimensions may be resorted to without departing from the spirit of the invention. 85

Having thus fully described the invention, what is claimed as new is—

1. A flexible tube having a spirally-wound metal strip formed with an inclosing member and a seat extending longitudinally thereof, 90 a packing-strip introduced in the successive seats and covered by the closing members, and a yielding coil having convolutions intersecting and closely fitting against the inner portions of the seats. 95

2. A flexible tube consisting of a spirally-

wound metal strip having oppositely-bent members to provide an outer box-like inclosure and an inner concave seat, the box-like inclosure successively interlocking with the 5 seats, a packing-strip introduced between the seats and box-like inclosures, and an inner sustaining-coil composed of resilient material and having the convolutions thereof closely fitting between and bearing upon the inner 10 portions of the seats.

3. A flexible tube having a spirally-wound metal strip with reversely-positioned bent members extending longitudinally thereof, the said bent members of the successive con-

volutions loosely interlocking, a packing-strip inclosed between the bent members, and a resilient sustaining-coil having the convolutions thereof closely fitting and bearing against the inner portions of the members and engaging the spaces between the latter. 15 20

In testimony whereof I have hereunto set my hand in presence of two subscribing witnesses.

SALVATORE SCOGNAMILLO.
